US0D1006445S

(12) **United States Design Patent** (10) Patent No.: **US D1,006,445 S**
(45) Date of Patent: ** Dec. 5, 2023

(54) **PILL BOX**

(71) Applicant: **Jinxi Zhou**, Changsha (CN)

(72) Inventor: **Jinxi Zhou**, Changsha (CN)

(**) Term: **15 Years**

(21) Appl. No.: **29/880,656**

(22) Filed: **Jul. 26, 2023**

(51) LOC (14) Cl. **03-01**

(52) U.S. Cl.

USPC **D3/203.2**

(58) **Field of Classification Search**

(57) **CLAIM**

The ornamental design for a pill box, as shown and described.

DESCRIPTION

FIG. 1 is a rear and top perspective view of a pill box, showing my new design;

FIG. 2 is a front and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front and top perspective view of the pill box of FIG. 1 in a use state; and,

FIG. 10 is a front and top perspective view of the pill box of FIG. 1 in another use state.

1 Claim, 10 Drawing Sheets
